ELECTRIC LAMP BASE

David Borowitz, Chicago, Ill.

Application September 14, 1954, Serial No. 32,274

Term of patent 3½ years

(Cl. D48—20)

To all whom it may concern:

Be it known that I, David Borowitz, a citizen of the United States, residing at Chicago, Illinois, have invented a new, original, and ornamental Design for an Electric Lamp Base, of which the following is a specification, reference being had to the accompanying drawing, forming a part thereof.

In the drawing:

Fig. 1 is a front elevational view of an electric lamp base showing my new design;

Fig. 2 is a top plan view thereof;

Fig. 3 is a right hand side view thereof; and

Fig. 4 is a back view thereof.

The broken lines indicating the socket of Fig. 1 have been omitted from Figs. 2, 3 and 4 for convenience of illustration.

A left hand side view would be the same as the right hand side view of Fig. 3.

I claim:

The ornamental design for an electric lamp base, substantially as shown and described.
